DESIGN FOR AN AIRSHIP

Justus W. Fry, Renton, Wash.

Application February 11, 1939, Serial No. 82,925

Term of patent 14 years

To all whom it may concern:

Be it known that I, Justus W. Fry, a citizen of the United States, residing at Renton, in the county of King and State of Washington, have invented a new, original, and ornamental Design for Airships, of which the following is a specification, reference being had to the accompanying drawings, forming part thereof.

Figure 1 is a perspective view of an airship, showing my new design;

Figure 2 is a front elevation;
Figure 3 is a top plan view; and
Figure 4 is a side elevation of the same.
I claim:
The ornamental design for an airship, as shown.

JUSTUS W. FRY.
